(57) **CLAIM**

The ornamental design for an accessory mounting bracket for a vehicle, as shown and described.

DESCRIPTION

FIG. 1 is a front perspective view of an accessory mounting bracket for a vehicle;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines showing of various portions and other elements in the Figures are for the purpose of illustrating unclaimed portions and form no part of the claimed design.

1 Claim, 6 Drawing Sheets
